Des. 237,313
Patented Oct. 21, 1975

237,313

PHYSICAL THERAPY EXERCISER

Eugene L. Harris, 1203 N. Euclid,
Anaheim, Calif. 92801

Filed July 26, 1973, Ser. No. 382,799

Term of patent 14 years

Int. Cl. D28—03

U.S. Cl. D83—1 S

FIG. 1 is a view in elevation of one side of the physical therapy exerciser;

FIG. 2 is a view in end elevation;

FIG. 3 is a bottom plan view;

FIG. 4 is a top plan view;

FIG. 5 is a view in elevation of the appliance showing the side opposite the side depicted in FIG. 1; and

FIG. 6 is an inverted view in end elevation of the appliance showing the end opposite the end depicted in FIG. 2.

I claim:

The ornamental design for a physical therapy exerciser, substantially as shown and described.
